UNITED STATES PATENT OFFICE.

GEORGE J. JONES AND EDWIN J. BLANNING, OF NEW CASTLE, PENNSYLVANIA.

EXTRACTOR FOR TUYÈRES AND TUYÈRE COOLERS.

Application filed March 1, 1927. Serial No. 171,793.

The object of the invention is to provide a simple, cheap and effective device by means of which tuyères or tuyère coolers employed in blast furnaces, or bushings of whatever kind may be readily removed where ordinarily held frictionally in place, without damage to the part removed or damage to the furnace wall at the opening designed to receive the tuyère and tuyère cooler; and to provide a puller or extractor by means of which an effective gripping action is applied on the inner periphery of the bushing or tuyère or tuyère cooler, increasing in force as the pulling or extracting operation progresses.

With this object in view, the invention consists in a construction and combination of parts of which a preferred embodiment is illustrated in the accompanying drawings, 20 wherein:

Figure 1 is a side elevational view of the invention shown in operative position, a portion of the wall of a blast furnace and the tuyère and tuyère cooler being shown in section.

Figure 2 is an end elevational view of the tool.

Figure 3 is a detail sectional view on the plane indicated by the line 3—3 of Figure 1. 30 Figure 4 is a sectional view on the plane indicated by the line 4—4 of Figure 1.

Figure 5 is an elevational view of a modified form of extractor.

Figure 6 is a view similar to Figure 1 35 showing the invention applied for the extraction or pulling of the tuyère cooler.

Figures 7 and 8 are respectively sectional views on the planes indicated by the lines 7—7 and 8—8 of Figure 6.

The invention is designed to make it possible, in the extraction of tuyères and tuyère coolers, or bushings of any kind where it is not possible to apply a pull on the end of the bushing to exert a gripping force on the inner periphery of the bushing or tuyère and to apply the pulling force directly axially of the bushing or tuyère. To this end the invention comprises a dolly bar 10 of uniform diameter for the greater portion of its length as indicated at 11 but of progressively increasing diameter as indicated at 12, to provide a tapering forward portion terminating in a head 14. On the tapering portion 12 the gripper 15 is slidably mounted, this gripper being formed with a central bore which permits free sliding movement of the gripper from the head 14 to a collar 16, the latter being mounted on the tapering portion 12 and retained in fixed position thereon by a pin 17, the latter extending 60 diametrically through the collar and through the tapering portion of the dolly bar. The gripper 15 is formed with a hub portion 18 counterbored to receive the collar 16, the hub being formed with diametrically disposed axial slots 19 communicating with circumferential slots 20, so that when the hub is seated on the collar the protruding ends of the pins 17 may enter the slots 19 and later enter the slots 20 by relative angular movement between the gripper and the dolly bar. Obviously when the pin is engaged in the slots 20, the gripper is locked in engagement with the collar 16 and the gripper is then at the smaller end of that 70 portion of the dolly bar which it is capable of traversing.

The gripper is provided with a plurality of uniformly spaced jaws 21 mounted for radial movement by means of shanks 22 slidably engaged in radial holes 23 formed in the gripper and limited in radial movement by stop screws 24 threadingly engaged with the head and having pilots 25 entering slots 26 in the shanks 22. The inner ends of the shanks 22 abut the tapering portion of the dolly bar and are shaped to conform thereto, the outer faces of the jaws 21 being serrated or toothed as indicated at 27 to provide gripping teeth to effect biting engagement 90 on the inner periphery of the bushing or tuyère to be extracted, such as the tuyère 28 illustrated in the drawings. When the gripper is engaged with the collar 16 and interlocked therewith by the engagement of the pin 17 in the slots 20, the jaws may occupy their innermost positions, so that the dolly bar may be employed for inserting the gripper in the tuyère 28 down to the point where there is slight frictional engagement between the faces 27 of the jaws 21 with the inner periphery of the tuyère 28. Then a slight angular or turning movement of the dolly bar will bring the pin 17 into registration with the slots 19, when relative angular movement between the dolly bar and the gripper is possible. The jaws, however, having slight frictional engagement with the tuyère are, when the dolly bar is withdrawn, forced into firm biting engagement 110 with the tuyère because of the wedging action of the tapering portion of the dolly

bar on the inner extremities of the jaw shanks.

The gripper having thus been engaged with the tuyère, the pulling operation may be continued by the application of a continuous pulling force on the dolly bar in the one form of invention shown or the application of sudden jars as in the other form. Where the tuyère is to be pulled or extracted by the application of blows intermittently applied to the dolly bar, the latter is provided with an impact member 28 slidably mounted on the straight portion 11 of the dolly bar and engageable with an abutment 29 secured to the dolly bar adjacent the end remote from the head 14. The impact member is provided with flexible hand actuating means 30 consisting preferably of steel cables engaged with the impact member and looped as indicated at 31 to provide hand grips. The members 30 are disposed on diametrically opposite sides of the impact member and thus may be held by two workmen who may readily apply a sudden pulling force to the impact member, sliding it along the straight portion 11 of the dolly bar until it engages the abutment 29, the impact member being then drawn back from the abutment and a second blow applied thereto in the same manner. Since the jaws in the gripper are actuated by the tapering portion of the dolly bar, each blow applied to the abutment tends to increase the gripping action and thus prevents slipping and the continuation of the application of blows to the abutment finally effects the withdrawal of the tuyère.

Where the application of the pulling force is to be gradual, that form of the invention illustrated in Figure 5 is employed. In this form of the invention, the gripper and the co-operating parts of the dolly bar are of the same form as shown in Figures 1 to 4 inclusive but the rear end of the bar is threaded as indicated at 32 for the reception of a nut 33 provided with radial arms 34 by means of which it may be readily turned. The threaded portion 32 of the dolly bar 10^a extends through a central opening in the spanner bar 35, the latter being disposed in spanning relation diametrically of the wall opening in which the tuyère cooler is inserted. The nut 33 engages the outer face of the spanner bar and as the nut is rotated, axial movement is thus imparted to the dolly bar 10^a with the same results as are secured with the dolly bar 10 in which axial movement is effected by means of the impact member and abutment.

In the extraction of the tuyère cooler 36, a pull plate 37 is employed, the latter having slots 38 cut in from the periphery at diametrically opposite sides to provide clearance spaces for the webs 39 on the tuyère cooler. By means of the slots 38 it is possi-

ble to insert the pull plate in the tuyère cooler behind the webs, after which a slight angular or turning movement will shift the slots out of registration with the webs. It is preferable that the turning movement be at least 90 degrees.

The pull plate is provided with a center slot 40 through which the T-head 41 of the dolly bar 10^a may be inserted, subsequent angular or turning movement of the dolly bar effecting an interlock between the head and the plate.

The plate is held in firm engagement with the inner edges of the webs 39 by means of bolts 42, the latter being disposed on diametrically opposite sides of the dolly bar and provided with nuts 43 abutting a clamp plate 44, spanning the opening in the furnace wall in which the tuyère cooler is received. The bolts 42 pass through the clamp bar and the dolly bar has a sliding engagement with the clamp bar.

The dolly bar 10^a is of uniform diameter throughout its length, carrying the sliding impact member 28 engageable with the abutment 29.

Since the tuyère cooler is of tapering form, but slight axial movement is necessary to loosen it and therefore the clamp plate 44 and bolts 42 maintain their position without the necessity for having to tighten the nuts, until the tuyère cooler is loose enough to be removed by hand.

The invention having been described, what is claimed as new and useful is:

1. A tool for the purpose indicated comprising a gripper provided with radially movable jaws, a dolly bar on which the gripper is slidably mounted and which has means for effecting radial movement of the jaws upon relative axial movement of the bar and gripper, releasable means for locking the gripper at a point on the bar where the gripper jaws have their inmost radial positions, and means for imparting axial movement to the dolly bar.

2. A tool for the purpose indicated comprising a dolly bar, a bushing engaging element carried at one end of the dolly bar, and means for imparting axial movement intermittently to the dolly bar consisting of an impact element slidably mounted upon the dolly bar and a fixed abutment on the dolly bar with which said impact element engages, the impact element having flexible actuating means.

3. A tool for the purpose indicated comprising a dolly bar, a bushing engaging element carried at one end of the dolly bar, and means for imparting axial movement intermittently to the dolly bar consisting of an impact element slidably mounted upon the dolly bar and a fixed abutment on the dolly bar with which said impact element engages, the impact element having flexible actuating means.

means consisting of cables secured to it at diametrically opposite sides and provided at their free end with hand holes.

4. A tool for the purpose indicated comprising a dolly bar provided at one end with a head and at a fixed point behind the head having a collar, that portion of the bar between the head and the collar being tapered, a gripper slidably mounted on the bar between the head and the collar and provided with radially movable jaws having shanks in sliding engagement with the tapered portion of said bar, the gripper and said collar having an interlocked connection releasable upon relative angular or turning movement between the gripper and the bar, whereby the gripper may be positively retained against the collar to secure the innermost

position of said jaws, and means for imparting axial movement to the bar.

20

5. A tool for the purpose indicated comprising a gripper provided with radially movable jaws, a dolly bar on which the gripper is slidably mounted and which has means for effecting radial movement of the jaws upon relative axial movement of the bar and gripper, and means for locking the gripper at a point on the bar where the gripper jaws have their inmost radial positions, said means being actuatable upon relative angular or turning movement between the bar and gripper.

In testimony whereof they affix their signatures.

EDWIN J. BLANNING.
GEORGE J. JONES.
